Inventor
Watson R. Smith,

By *[Signature]* John Smith

Attorney

UNITED STATES PATENT OFFICE.

WATSON R. SMITH, OF JACKSON, MICHIGAN.

SPRING STRUCTURE.

Application filed June 18, 1921, Serial No. 476,522. Renewed February 21, 1924.

To all whom it may concern:

Be it known that I, WATSON R. SMITH, a citizen of the United States, residing at Jackson, in the county of Jackson and 5 State of Michigan, have invented new and useful Improvements in Spring Structures, of which the following is a specification.

This invention relates to spring structures.

10 One object is to provide a sheet metal base frame composed of a sheet metal strip having a downwardly opening recess and upper and lower flanges along its inner side adapted to form an inner longitudinal 15 groove to receive a spring structure element in which groove the element is held by compression of one or both flanges, the said recess being adapted to confine or retain a wood insert or analogous material 20 to which the marginal edge of the upholstering covering of the structure may be tacked along the bottom of the folded strip.

Another object of the invention resides 25 in the provision of a base frame having a recess which opens through the lower face of the frame and in which suitable means is confined and to which the upholstering covering may be secured, the frame also 30 having upper and lower flanges along its inner side forming a longitudinal groove to receive one of the spring structure elements, the lower flange lying in a plane lower than any other portion of the frame 35 so as to sustain the weight of the spring structure and hold the outer edge of the base frame away from the usual support on which the structure is mounted and thereby prevent undue wear on the cover along 40 the outer lower edge of the frame where the cover is turned inwardly under the frame.

With the above and other objects in view, the invention consists in the novel construction, combination and arrangement of parts hereinafter fully described, illustrated in the accompanying drawings and pointed out in the claims hereto appended, it being understood that various changes in the 45 form, proportion and minor details of construction, within the scope of the claims, may be resorted to without departing from the spirit or sacrificing any of the advantages of the invention.

55 In the drawings in which like characters

of reference designate corresponding parts in the several figures:

Figure 1 is a fragmentary inverted plan view of the invention.

Figure 2 is a transverse sectional view 60 showing the position of the base frame with relation to the support upon which the spring structure is positioned.

Referring now more particularly to the accompanying drawings, the reference character A indicates the base frame, the character 65 3 indicating border springs connected to the frames.

The essential feature of the present invention goes to the base frame B which is 70 composed preferably of sheet metal in the form of a folded strip, the metal being folded to form a relatively wide recess 6 in which a wood insert or other filler 7 is confined, the recess having a longitudinal opening 75 in its lower face, throughout its length, to expose the material 7. The marginal edge of the skirt 8 of the upholstering covering is turned under the outer rounded edge of the strip and over the said opening 80 in the frame and may be tacked to the wood insert or analogous material 7. The tacks for securing the upholstering to the base frame are indicated at 9 and may be 85 of such length that when driven through the covering and the wood or analogous material 7 they contact with the inner face of the top of the metallic frame strip and become clinched to prevent accidental disconnection. 90

The inner side of the sheet metal strip is folded in such a manner as to provide upper and lower flanges 10 and 11, respectively, along the entire inner edge of the base frame strip, the upper flange lying 95 preferably in a plane slightly below the lower face of the filling material 7 and also preferably slightly below the longitudinal opening in the under face of the base frame strip so that the spring structure as a whole 100 is supported from the inner side of the base frame strip on the lower flange to hold the turned in marginal edge of the upholstered covering off of the support on which the structure is mounted and thereby prevent 105 undue wear of the covering at the outer lower edge of the base frame where it is turned in under the frame.

I claim—

1. In a spring structure, a base frame 110

- whose body portion is composed of a strip of wood and a strip of sheet metal folded over the wood strip to completely conceal the latter save for a narrow part along the 5 under side thereof adjacent the inner side of the wood strip, said metal strip, along the inner side of the said body portion being directed inwardly in reverse S-formation to provide an inwardly opening groove within 10 the said body portion and whose lower wall lies in a plane within the wood strip and lower than the plane of the under side of the wood strip so as to support the afore- 15 said base frame from within the confines of the wood strip and thereby maintain the aforesaid exposed part of the wood strip on a level higher than the lower wall of said groove, springs having connection with said groove, a covering drawn under the body portion of the base frame, and tacks piercing 20 the marginal edge of the covering and the wood strip adjacent said reverse S-formation and upset against the upper wall of said groove.
- 25 3. A base frame for spring structures composed of a body portion including a fibrous strip and a strip of sheet metal folded over the fibrous strip and at the inner side of the body portion folded to provide an inwardly opening groove lying in a plane within the 30 vertical inner side of the body portion with its rear closed wall abutting against the inner side of the fibrous strip and having its lower wall lying in a horizontal plane lower than the horizontal plane of the under side of the fibrous strip to act as a supporting ledge within the inner vertical confines of the fibrous strip to maintain the fibrous strip elevated slightly above the horizontal plane 35 of the lower wall of the groove.
- 25 4. In testimony whereof I have hereunto set my hand.
- 25 5. WATSON R. SMITH.
